UNITED STATES PATENT OFFICE.

JOHN TEUSCHER, JR., OF BRIDAL VEIL, OREGON.

SUSPENSORY BANDAGE.

SPECIFICATION forming part of Letters Patent No. 531,232, dated December 18, 1894.

Application filed July 25, 1894. Serial No. 518,569. (No model.)

To all whom it may concern:

Be it known that I, JOHN TEUSCHER, Jr., a citizen of the United States, residing at Bridal Veil, in the county of Multnomah and 5 State of Oregon, have invented a new and useful Suspensory Bandage, of which the following is a specification.

My invention relates to an improvement in suspensory bandages, and it consists in a 10 suspensory bandage which is provided with a roll or pad of absorbent material at its upper rear edge, which is also provided with rubber connections between the divided portions of the belt, as will be more fully described here- 15 inafter.

The object of my invention is to provide a suspensory bandage which is not only made of absorbent material, but is supported in such a manner that it will not slip down, will 20 always adjust itself to the person of the wearer, and is simple and durable in construction.

In the accompanying drawings Figure 1 is a front elevation of a suspensory bandage 25 which embodies my invention. Fig. 2 is a vertical section taken on the line $x-x$, of Fig. 1. Fig. 3 is a perspective of the rubber connection which unites the two parts of the belt.

A represents the suspensory bag which is 30 preferably made of cotton flannel, not only because this material absorbs perspiration, but because it is soft and durable. Other absorbent materials may be used such as silk, or silk knitting, but cotton flannel is preferred because it has been found best adapted for this purpose. The bag is made of two 35 pieces of material which are sewed together by two seams α all around its outer edges, so that if it should be slightly too small the outer row of stitches can be ripped open, and 40 the bag thus correspondingly enlarged. Applied to the upper rear edge of the bag is the roll or pad B of velvet, which extends nearly across the top of the bag. This roll or pad 45 decreases the size of the suspensory bag, and fits just behind the testicles of the wearer. It gives a firm yet easy support, it holds the bag in place, and assisted by the short straps C preserves its shape. This roll or pad must

not extend the whole width, so that the sides of 50 the bag may adjust themselves to the parts more easily. Through the front of the bag is made the usual opening through which the penis passes. Attached to the two upper corners of the bag are the two short straps or 55 belts C, which are adjusted to the bag at such an angle as to pull sidewise as well as upward. These two belts C are quite short, and are made separate from the main belt G, but connected thereto by the elastic strips I. These 60 elastic strips are placed on the outer side of the belt, so as to be protected from perspiration from the body at that point where the ends of the straps and belts meet. These two short pieces of elastic are applied at the 65 points shown, and help to make the suspensory bandage self-adjusting and comfortable to the wearer.

Fastened to the main belt G just above the elastics is the auxiliary cross belt J which 70 extends across the abdomen at such a point as not to interfere with abdominal breathing. This belt is left about two inches too long, so that a corpulent man can adjust the same enough to enable the two short belts C to fit 75 in the groins. By means of this auxiliary cross belt, the belt G can be tightened and held at exactly the same height during the entire day without inconvenience. It is this tendency of the bag to slip down out of place 80 that necessitates the use of elastic in the suspensory bandage and often straps around the thighs in some of the suspensory bandages now in use, which makes them uncomfortable and often painful.

Where a suspensory bandage is constructed as here shown, fits the person, and is made of absorbent material so as to absorb the perspiration from the parts, the wearer is saved much suffering, and the suspensory will in 90 many cases cure and prevent varicose veins.

Having thus described my invention, I claim—

In a suspensory bandage, a bag consisting of two duplicate parts adjustably seamed 95 together at their meeting edges, an absorbent roll or pad extending partially across the upper rear edge of said bag, a pair of short

straps attached to the front corners of the bag and disposed at an angle thereto, the main body belt having an auxiliary cross belt connecting the opposite side portions thereof, and 5 elastic strips connecting the adjacent ends of said short connecting straps and the main body belt, substantially as set forth.

In testimony that I claim the foregoing as my own I have hereto affixed my signature in the presence of two witnesses.

JOHN TEUSCHER, JR.
